UNITED STATES PATENT OFFICE.

WILLIAM J. JUDD, OF NEW YORK, N. Y.

MIXER.

1,129,102.

Specification of Letters Patent. Patented Feb. 23, 1915.

Application filed July 2, 1909. Serial No. 505,578.

To all whom it may concern:

Be it known that I, WILLIAM J. JUDD, a citizen of the United States, residing in New York city, in the county of New York and State of New York, have invented certain new and useful Improvements in Mixers, of which the following is a specification.

This invention relates to machines for mixing concrete and other materials.

10 The principal object of the invention is to provide at low cost an effective machine of this character and particularly one that can be charged and discharged without stopping the machine.

15 My improvements are illustrated preferably in connection with a cubiform mixing barrel. Within the barrel I provide a vane, which during the mixing operation carries the material upwardly, and drops it from

20 the top to the bottom of the barrel, thus aiding in the mixing. Within the discharge opening of the barrel I project the small end of a discharge bell, and in said bell I provide a lateral opening which may receive the

25 discharge from said vane, and conduct the same out of the mixer. Relative rotative shifting may be effected between the bell and the drum so that said lateral opening in the bell shall no longer be in communication

30 with said vane, so that the contents of the barrel may continue to mix instead of discharging. I provide simple means for effecting the relative shifting movement of the bell, to bring the lateral opening there-

35 in into and out of coöperation with said vane at will.

Other objects and advantages will herein-after appear.

In the accompanying drawings, Figure 1 is a sectional elevation of the apparatus taken about axially of the mixing barrel. Fig. 2 is an elevation of the charging end of the apparatus. Fig. 3 is an elevation of the discharging end of the apparatus, showing the discharge bell as shifted to a position to prevent discharge from the barrel during the revolution thereof. Fig. 4 is a similar view showing the discharge bell shifted to a position to receive the discharge from the in-

45 terior vane in the barrel; such discharge occurring once in every revolution when said vane is in elevated position. Fig. 5 is a fragment of a stop lever showing the manner of mounting a stop thereon. Fig. 6 is a 55 elevation similar to Fig. 4, but showing means for arresting the discharge bell dur-

ing the revolution of the barrel to effect a rotative dislocation of the bell, to prevent the same from receiving or discharging the contents of the barrel. Fig. 7 is a side elevation of the apparatus as seen at Fig. 3. Fig. 8 is a plan of the apparatus with the parts in positions seen at Fig. 3. Fig. 9 is a perspective view of the vane or shovel secured within the mixing barrel.

The mixing barrel 1, which may be of any form, is illustrated as cubiform, having at its ends wheels 2, 3 which forms a part thereof, said wheels riding upon antifriction rolls 4, 5; a gear 6 formed on the wheel 60 3 being driven by a pinion 7 loose on a shaft 8, and a clutch mechanism 9 being provided to connect the pinion to the power shaft. The latter may be driven by an engine 10 through a pinion 11 and a gear 12. The materials to be mixed are thrown into a hopper 13 at the receiving end of the barrel. This hopper is supported by a standard 14 rising from the base or sill 15 of the apparatus. At its lower end the hopper terminates in or 65 is secured to an annular mouth-piece 16 having a brim 17, which rolls over an annular internal lip 18 formed in the plate having therein the charging opening 19 of the barrel. The hopper comprises a vertical 70 rear plate or apron 20, which is secured at its bottom by bolts 21 passing into the mouth-piece 16, and the latter has a depending lug 22 secured to said supporting standard 14. The charging orifice 19 is formed in a triangular plate 23, which is cast integral with the wheel 2, and is formed along all sides with stiffening flanges 24.

To prevent access of grit between the over-curved brim 17 and the inwardly projecting lip 18, I provide a guard-ring 25, which may be formed in three similar segments, secured by bolts 26 to said flanges 24; each segment having at its ends ears 27 through which the bolts pass; said ears being inclined to correspond to the inclination of the flanges 24. Said flanges 24 are inclined to fit the sides of the cubical barrel at its truncated end, as illustrated clearly at Fig. 1. The sides of said barrel are inserted between said flanges and said ears 27, and are secured by the same bolts 26 that hold the ring-segments 25.

The standard 14 is made adjustable vertically to compensate for irregularities in manufacture, and also to permit vertical adjustment of the mouth-piece 16 of the hop-

per, to accommodate settling of the barrel due to wear of the trundles and bearings. This adjustment is effected by a screw 28 passing down through a lug 29 secured to the rear face of the standard 14, and bearing upon a metal plate or step 30 provided on the framework 15. The standard 14 is held fast by means of a pair of vertical clamps 31 secured by horizontal bolts 31^a to the side of the frame or sill 15. These clamps may be loosened to permit vertical adjustment of the standard, and may then be tightened to hold the standard where adjusted. At its opposite end the mixing barrel is supported in a similar manner. A triangular plate 32 having flanges 33 and formed integral with the wheel 3, is provided with a discharge orifice or opening 34 at the axis of revolution. Inserted in said discharge orifice 34 is a discharge funnel or bell 35, having a peripheral collar or flange 36 to fit in a depression 37 formed in the exterior edge of the orifice 34 (the mixing barrel and bell being relatively revoluble). The bell is held in place by a ring 38 secured by screws 39 to the triangular plate 32, and there is sufficient friction at the joint to cause the bell to turn with the barrel, while permitting the bell to be held stationary when desired during the turning of the barrel, to effect a shift of their relative positions.

For convenience, the part of the bell which projects within the barrel may be cast, and may have the flange 36 thereon; and the remainder of the bell may consist of a sheet metal cone frustum 35^a fitted to the cast portion 35, and bearing against a shoulder 40 formed thereon. The inner end 41 of the bell is closed, as at 41; the bell extending preferably half way of the length of the barrel.

During the mixing operation, none of the material enters the bell 35; but after the material is thoroughly mixed, it is discharged into said bell through a long lateral slit or opening 42 formed therein and extending from its inner end nearly to the flange 36. At Fig. 3 this opening is shown in such position that the mixed material cannot be received into the discharge bell.

A vane or shovel 43 is employed for the purpose of conveying the mixed material into the discharge bell; and it will be seen that when it is not desired to discharge, it is only necessary to change the location of the opening 42 with reference to the shovel 43, as at Fig. 3. By subsequently effecting another relative turning movement between the bell and the shovel, the opening 42 may be brought again into position to receive the discharge of the vane or shovel 43, whereupon some of the mixed material will be deposited in the discharge bell at each revolution of the barrel, when the shovel 43 is suffi-

ciently raised to permit the material to flow therefrom through the opening 42, as will be understood by reference to Fig. 6.

From the foregoing it will be understood that the discharge bell 35 is intended usually to revolve with the barrel, and at each revolution to receive and discharge a portion of the contents of the barrel; but the bell is capable of rotative shifting within the barrel, so that even though both revolve together, none of the contents of the barrel can get into the bell or be discharged. To effect conveniently this relative shifting between the bell and the barrel, I provide a suitable stop mechanism to arrest the bell during the revolution of the barrel, to bring the bell slot 42 to either effective or ineffective position, as may be desired. The mixer may continue to rotate always in the same direction without stopping for charging or discharging.

Upon the bell I provide two stops or lugs 44 and 45. These lugs may be in the form of bolts which connect two segments 46 of a ring which encircles the bell just outside of the barrel; said segments formed with ears 47 through which the bolts extend, and by which the segments are drawn tightly upon the bell, so as not to shift accidentally around the same. A coöperative stop 48 is secured upon a lever 49, pivoted at 50 upon the framework, and having a handle 51. Said stop 48 is normally idle, the lever 49 resting upon a pin 52 provided upon a fixed vertical guide 53. Upon lifting the lever, the stop 48 may be brought into the path of either lug 44 or 45, to arrest the bell while the barrel continues to rotate, thereby to effect the desired relative shifting of the barrel and bell. The bell may thus be brought alternately to effective and ineffective positions.

Assuming that the materials are mixed and are ready to discharge, the lever 49 is lifted from the position at Fig. 3 to that at Fig. 4, to intercept the stop or lug 44 and hold the bell still until the barrel 1 and its internal shovel 43 swing from the position at Fig. 3 to that at Fig. 4. In the latter position the shovel (which at each revolution carries up a portion of the contents of the mixer) registers with the opening 42 in the cone or bell 43, so that as the two continue to rotate together in the direction of the arrow, the shovel will be enabled once in each revolution of the mixer to discharge its contents through said opening 42 into the bell; the mixed materials sliding down the sloping floor of the bell and out of the machine.

If desired, the stop 48 may be caused automatically to release the bell when the parts are at the Fig. 4 position. For this purpose a latch 54, pivoted at 55 upon the framework, may engage a

pin 56 projecting from the lever 49, to hold it in the Fig. 4 position; and a tappet 57 projecting from the end of the revolving barrel may knock said latch toward the left 5 at Fig. 4, thus releasing the lever and permitting the latter to drop. The latch may be connected to the lever by a link 58, which during the rising of the lever, swings the latch to the Fig. 4 position; the joints being 10 made sufficiently loose for the requisite play of the parts. The bell having thus been adjusted, the contents of the mixer are discharged.

Before introducing a new charge into the 15 hopper 13, the handle 51 is again lifted to carry the stop 48 into the path of said lug 44 or of the lug 45 (which is diametrically opposite from the lug 44 on the cone 35). The bell is thus again stopped, while the barrel 20 continues to revolve; and when the bell and barrel reach the relative position at Fig. 3, the tappet 57 again releases the latch 54, and the lever 49 again drops; so that any discharge from the shovel 43 will fall upon 25 the crown of the bell 45 and from thence drop again to the bottom of the revolving barrel. The shovel and the bell thus aid in mixing the material, so that the mixing operation occupies a minimum of time; while 30 at any time by lifting the handle 51, said shovel 43 and bell 35 may be brought into coöperation to discharge the barrel.

The lugs 44 and 45 are placed upon opposite sides of the cone, so that either lug may 35 operate for effecting adjustment of the bell either to the position at Fig. 3 or to that at Fig. 4, or vice versa; and the mounting of the lugs upon the ring 46 permits their adjustment relatively to the discharge opening 40 42 of the bell, so that by adjusting said ring, the opening 42 may be brought to the proper position relative to the shovel 43 at the moment that the tappet 57 releases the lever 49.

45 Variations may be resorted to within the scope of the invention, and portions of the improvements may be used without others.

Having thus described my invention, I claim:

50 1. In a mixing machine, the combination with a barrel having a charging opening provided with an annular internal lip, of a hopper terminating in an annular mouth-piece having a brim which rolls over said 55 lip, said hopper comprising a rear plate or apron which is secured at its bottom to said mouth-piece.

2. In combination, a truncated cubiform mixing barrel, triangular frames to which 60 the truncated ends of the barrel are secured, said frames having stiffening flanges inclined to fit the adjoining sides of the barrel, and wheels cast integral with said frames.

55 3. In a mixing machine, the combination

with a barrel having a charging opening provided with an annular internal lip, of a hopper terminating in an annular mouth-piece having a brim which rolls over said lip, and a guard ring surrounding said brim 70 and secured upon the barrel.

4. In combination, a cubiform mixing barrel having a truncated end, a triangular frame having a charging orifice and provided with stiffening flanges inclined to fit 75 the adjoining sides of the barrel, said charging opening provided with an annular internal lip, a hopper terminating in an annular mouth-piece having a brim which rolls over said lip, a dust guard ring surrounding said brim and having ears within the barrel, and bolts passing through the ears, barrel and the frame, to secure them together.

5. In combination, a cubiform mixing 85 barrel having a truncated end, a triangular frame having a charging orifice and provided with stiffening flanges inclined to fit the adjoining sides of the barrel, said charging opening provided with an annular internal lip, a hopper terminating in an annular mouth-piece having a brim which rolls over said lip, a dust guard ring surrounding said brim and having ears within the barrel, and bolts passing through the ears, 90 barrel and the frame, to secure them together, said dust guard ring formed in three single segments, and said ears provided at the ends of said segments.

6. In a mixing machine, the combination 100 with a revoluble mixing barrel, of a hopper terminating in an annular mouth-piece fitted to a charging opening in said barrel, a standard which is supported upon the framework of the apparatus for vertical adjustment; said hopper supported on said standard; said standard having a lug and a screw threaded through said lug and bearing upon said framework for effecting the vertical adjustment of the standard; and independent clamping devices adapted 105 to be secured to said standard and frame to hold the standard fast where adjusted.

7. The combination of a mixing barrel 110 having a discharge opening, a self-discharging bell mounted to revolve with said barrel and extended through said opening, said bell having a lateral opening within the barrel, lugs on said bell, a device for preventing at will the contents of said barrel 115 from entering said opening, said device having a movable stop for engagement with said lugs.

8. In combination, a mixing barrel, a self-discharging funnel or bell extending 120 through a discharge opening in said barrel and mounted to rotate therewith and having a lateral opening, and constructed to discharge the barrel by reason of the revolution of the latter, said mixing barrel having 125 130

- an internal vane, shovel or conduit, said bell and barrel being shiftable rotatively to bring said lateral opening either into or out of position to receive the discharge from said vane, lugs on said bell and a stop for engagement with one or the other of said lugs.
9. In combination, a mixing barrel, a self-discharging funnel or bell extending through a discharge opening in said barrel and mounted to rotate therewith and having a lateral opening, and constructed to discharge the barrel by reason of the revolution of the latter, said mixing barrel having an internal vane, shovel or conduit, said bell and barrel being shiftable rotatively to bring said lateral opening either into or out of position to receive the discharge from said vane, and means including a manually operable member, for effecting such relative shift between the bell and barrel during the rotation of the barrel, said manually operable member mounted upon the framework to be normally stationary during the rotation of the barrel.
10. In combination, a mixing barrel, a self-discharging funnel or bell rotating therewith and projecting thereinto at the axis of the barrel and having a peripheral collar or flange to fit in a depression formed in the exterior edge of the orifice in the barrel through which the bell projects, and a ring secured to the barrel to engage said flange to hold the bell in place; said barrel having an internal vane, and said bell having within the barrel an opening, and being rotatively shiftable to bring said opening into or out of position to receive the discharge from said vane.
11. In combination, a mixing barrel, a self-discharging funnel or bell projecting thereinto at the axis of the barrel and having a peripheral collar or flange to fit in a depression formed in the exterior edge of the orifice in the barrel through which the bell projects, and a ring secured to the barrel to engage said flange to hold the bell in place; said barrel having an internal vane, and said bell having within the barrel an opening, and being rotatively shiftable to bring said opening into or out of position to receive the discharge from said vane; the bell and barrel being frictionally jointed to cause the bell to rotate with the barrel.
12. In combination, a mixing barrel, a self-discharging bell of cast metal projecting thereinto at the axis of the barrel and having an integral peripheral collar or flange cast thereon and formed to fit in a depression formed in the exterior edge of the orifice in the barrel through which the bell projects, and a ring secured to the barrel to

engage said flange to hold the bell in place; said bell having within the barrel an opening to receive the contents from the barrel, and being rotatively shiftable to bring said opening into or out of effective position; the bell and the barrel being frictionally jointed to cause the bell to rotate with the barrel, and a mouth-piece fitted to the outer end of said bell.

13. The combination with a revoluble mixing barrel, of a discharging bell provided with lugs, mounted to rotate with said barrel, and a lever adapted to be brought into engagement with either of said lugs, whereby said bell may be held adjusted relative to the barrel.

14. The combination of a revoluble mixing barrel having a self-discharging bell to revolve therewith, means connected to the barrel being provided for effecting the transfer of the contents of the barrel to said discharge bell, the latter having an opening to receive such contents and rotatively shiftable with reference to the barrel to prevent such contents from entering the bell, a lug provided on the bell, and a stop movable into the path of said lug to hold the bell stationary during the revolution of the barrel.

15. The combination of a revoluble mixing barrel having a discharge bell to revolve therewith, means being provided for conveying the contents of the barrel to said discharge bell, the latter having an opening to receive such contents and rotatively shiftable with reference to the barrel to prevent such contents from entering the bell, a lug provided on the bell, a stop movable into the path of said lug to hold the bell stationary during the revolution of the barrel, a latch to hold said stop in working position, and means connected to the barrel for releasing said latch.

16. The combination of a revoluble mixing barrel having a discharge bell to revolve therewith, means being provided for conveying the contents of the barrel to said discharge bell, the latter having an opening to receive such contents and rotatively shiftable with reference to the barrel, to prevent such contents from entering the bell, a lug provided on the bell, a stop movable into the path of said lug to hold the bell stationary during the revolution of the barrel, a latch to hold said stop in working position, means connected to the barrel for releasing said latch, said stop mounted upon a lever, and a link connecting said lever to said latch.
